UNITED STATES PATENT OFFICE.

HENRY EDWARD WINANS, OF POUGHKEEPSIE, NEW YORK.

SINGLE-TRIGGER FIREARM.

SPECIFICATION forming part of Letters Patent No. 769,524, dated September 6, 1904.

Application filed August 6, 1903. Serial No. 168,436. (No model.)

To all whom it may concern:

Be it known that I, HENRY EDWARD WINANS, a citizen of the United States, and a resident of Poughkeepsie, in the county of Dutchess and State of New York, have invented a new and Improved Single-Trigger Firearm, of which the following is a full, clear, and exact description.

My invention relates to improvements in that class of firearms which employ a single trigger in connection with the two locks of a double-barreled gun.

A practical and successful device of this character must fulfil two important requirements—first, freedom from a tendency to discharge both barrels in rapid succession by an involuntary pull on the trigger, and, secondly, the ability of the user to select at will the right or left barrel for service.

The device to be hereinafter described as one embodiment of the present invention meets both of these requirements by an extremely simple, efficient, and durable construction which is not liable to get out of order and which may, furthermore, be easily removed, repaired, and replaced without dismantling the other elements of the firearm.

Further objects and advantages of the invention will appear in the course of the subjoined description, and the novelty will be defined by the annexed claims.

Reference is to be had to the accompanying drawings, forming a part of this specification, in which similar characters of reference indicate corresponding parts in all the figures.

Figure 1 is an elevation of a firearm with parts broken away and showing my improved single-trigger mechanism in side view. Fig. 2 is a vertical longitudinal sectional view through the parts comprising the improved trigger devices removed from the firearm. Fig. 3 is a plan view of the parts shown by Fig. 2, illustrating a laterally-adjusted position of the selective trigger by dotted lines. Fig. 4 is a vertical cross-section through the stock of the gun, illustrating the relative positions of the two gun-locks to the single-trigger device of my invention; and Fig. 5 is a

horizontal longitudinal section through the single-trigger device on the dotted line 5 5° of Fig. 2.

In Figs. 1 and 4 of the drawings I have shown my single-trigger device as applied to a double-barreled shotgun of that type known as "breakdown hammer-guns;" but it 55 will be understood that I do not desire to confine my invention to this particular type of firearms, because I reserve the right to employ the single-trigger mechanism in connection with any kind of double-barreled gun. 60

A designates a portion of the standing breech, which contains the firing-pins b, adapted to be acted on by the hammers B C for the right and left gun-locks D E, respectively. A portion of the gun-stock is indicated by 65 dotted lines at F in Fig. 1, and one of the barrels is indicated at G in the same figure. Each gun-lock is of ordinary construction in that it embraces a mainspring c and a sear, the sear for the right-hand gun-lock D being indicated at d, and the sear for the left-hand gun-lock E being indicated at d' in Fig. 4. The construction of the gun and its locks may be similar to any approved type of firearm, and the only change which I have 70 made in this part of the gun consists in the arrangement of the tailpieces e e' in different horizontal planes on the sears d d', respectively, said tailpieces e e' extending inwardly and toward each other from the respective 75 sears d d', and in the normal positions of the sears (when both of the gun-locks are cocked) said tailpieces e' for the left-hand sear d' lie somewhat below the horizontal plane of the tailpiece e of the right-hand lock-sear d, as 80 shown in Fig. 4.

The stock F of the weapon is recessed or cut away, as is usual in the art, for the accommodation of the several parts entering into the structure of the gun, at the breech portion 90 thereof, and to the lower or under side of this stock is attached a trigger-plate 5. The trigger-plate is shown as having an upstanding post 6, in which is produced a threaded socket 7, adapted for the reception of one of the 95 screws by which the trigger-plate is fastened

to the gun-stock. The trigger-plate is provided at a point intermediate of its length with a longitudinal slot 8, in which is arranged to play a blade 9 of an ordinary trigger 10. This blade of the trigger is provided with an upwardly and forwardly extending ear 11, and the upper rear part of said trigger-blade is provided with a straight inclined sear-engaging face 12 and with a shouldered portion 13, which forms another sear-engaging face 14, the latter lying in an inclined plane parallel to and below the sear-engaging face 12 of the trigger-blade, as shown more particularly by Fig. 2.

15 15 designates a carrier for the trigger, the same being mounted upon the trigger-plate 5 so as to be capable of a lateral shifting movement thereon, whereby the trigger is adapted to be brought into coöperative relation to the 20 tailpieces on the sears of the right and left gun-locks. This carrier is shown in the form of a block, which is provided with a tubular depending boss 16, that is fitted revolvably in an opening of the trigger-plate in order that 25 the carrier may be mounted pivotally on said plate. The pivotal boss of the carrier is formed with a threaded socket, which is adapted to receive the threaded shank of a headed screw 17, that is arranged to act against the 30 under side of the carrier-plate and to confine the carrier 15 to pivotal movement on said trigger-plate. The carrier is forked or bifurcated, so as to provide a longitudinal slot or kerf 18, in which is loosely fitted the forwardly 35 and upwardly extending ear 11 of the trigger-blade 9, and this trigger-blade is connected pivotally to the laterally-swinging carrier by a transverse pin 19, which passes loosely through the ear and is fixed in the carrier at 40 the upper forward end thereof. The carrier is capable of turning in a lateral direction and on a vertical axis afforded by the pivotal stud 16 and the screw 17; but the pin 19 is arranged in a horizontal position, so as to afford an axis 45 of movement for the trigger 10, said axis of the trigger being horizontal and at right angles to the axis of the carrier 15, as will be readily understood by reference to Fig. 2. The carrier is normally impelled in one direction 50 by means of a spring 20, the same being secured by a screw 21 to the upstanding post 6 of the trigger-plate, and this spring is disposed laterally with respect to the carrier for its free end to engage with one side of the carrier in 55 order to force said carrier and the trigger toward the right-hand side of the gun-stock, whereby the trigger occupies a position for the face 12 to lie below the tailpiece *e* of the sear *d* of the right-hand gun-lock *D*. The 60 trigger 10 and its blade 9 are normally depressed, so that the front edge of the trigger-blade engages with an adjustable stop-screw 9^a, which is attached to the pivoted carrier, and this trigger is pressed against the stop-

screw by the employment of a spring 22, the 65 same being arranged above the trigger-blade and attached to the trigger-carrier 15 by a screw 23. The spring 22 is thus mounted on the carrier for lateral shifting movement therewith, and it normally engages with the 70 blade of the trigger in order to depress the latter to a position below the tailpieces of the sears forming parts of the two gun-locks.

In the drawings I have shown each of the 75 springs 20 and 22 as consisting of two flat plates of metal imposed one upon the other in a way to form compound leaf-springs; but it will be understood that I do not strictly confine myself to this special form of spring.

The shoulder 13 at the rear part of the trigger-blade may be made in one piece with said blade, or it may be made by a flat plate secured in the desired position to the blade; but in either case this shoulder should be provided with a rearwardly-extending tooth or 85 spur 24. With this tooth is adapted to engage a locking-detent, which is shown in the form of a plate 25, that is slidably mounted on the trigger-plate 5 in a position for engagement with said tooth 24 of the trigger-blade. The plate 25 is provided with a longitudinal slot 26, through which passes a limiting-screw 27, the latter being fastened to the trigger-plate. The rear part of the 90 slideable detent is provided with a stem 28, the latter 95 being slidably fitted in an upstanding chambered guide 29, provided on the rear part of the trigger-plate 5. Around the stem of the slideable detent is fitted a coiled spring 30, which is contained in the chamber of the 100 guide 29 and is arranged to act against the detent in a way to normally impel the latter to a forward position. The front end of this detent 25 is provided with a lip 32, arranged to form a shoulder 33 on one side, the other 105 side of the lip 32 being beveled in two directions, as shown by Fig. 3. The slideable detent 25 is furthermore provided with a depending ear 34, having a serrated lower edge 110 and forming a thumb-piece which is extended below the trigger-plate and is normally exposed to view outside of the gun-stock, so that it occupies an exposed position and is readily accessible by the finger or thumb of the operator in a way to permit the detent to 115 be operated by hand at any time.

The tendency of the spring 20 is to force the carrier and the trigger toward one side of the slot in the trigger-plate, and owing to the strength of this spring and the extended area 120 of the trigger-blade 9 considerable friction is liable to take place between one wall of the slotted trigger-plate and one face of the trigger-blade. To minimize the friction, I employ a stud or pin 35, which is secured to the trigger-plate in position to fit in a recess 36, which is provided in one face of the laterally-swinging trigger-carrier 15, said pin serving as a 125

stop in limiting the movement of the trigger-carrier under the influence of the spring 20 and in retaining the trigger-carrier and the trigger-blade in such positions that said trigger-blade will not have frictional engagement with one wall of the slot. The small stop or pin 35 provides a minimum amount of surface for the frictional engagement of the trigger-carrier therewith.

It will be observed that the trigger-plate carries all the parts of the trigger mechanism except the gun-locks, and this trigger-plate is adapted to be easily and quickly dismounted from the gun-stock, so that ready access can be obtained to any of the parts of the trigger mechanism for the purpose of cleaning, oiling, or repairing the same.

After the parts shall have been properly assembled the trigger and its carrier are held by the spring 20 in position for operating the right-hand gun-lock D. This spring 20 acts on the carrier to press the latter against the stop 35, and said carrier determines the position of the trigger, wherein the sear-engaging face 12 lies below the tailpiece e of the right-hand gun-lock sear d, substantially as shown by Fig. 4. If it is desired to explode the charge in the right-hand barrel, the operator cocks the hammer B and pulls the trigger, which turns on the pivot 19 and is raised for the face 12 to engage with the sear-tail e, thus releasing the sear of the right-hand lock D, whereupon the spring c impels the hammer forcibly against the right-hand firing-pin b, thereby exploding the cartridge in the barrel. The blade 9 of the trigger and the sear-faces 12 14 are very narrow, as shown by Fig. 3, and this blade of the trigger is arranged to play in the space between the inwardly-extending tailpieces e e' of the two sears. If it is desired to discharge a cartridge in the left-hand barrel, the trigger should be operated by a pull in a lateral and rearward direction, thereby shifting the carrier 15 on the vertical axis afforded by the stud 16 and moving the trigger-blade on the pin 19 in a vertical direction, thus bringing the sear-face 14 of the trigger-blade into engagement with the tailpiece e of the left-hand sear, whereupon the hammer of the left-hand lock is actuated by the hammer-spring so as to strike the left-hand firing-pin b and explode said charge.

One of the important features of my invention is the ability of the sportsman to select either the right or left cartridges for service, and in this connection it is to be observed that the trigger and the coöperating detent allow said trigger to be adjusted to operate the right lock and then the left lock, or vice versa, as may be desired. It should be borne in mind that in the normal position of the trigger it is adjusted to actuate the right lock; but the operator can press the trigger laterally toward the left, so as to turn the trigger and the car-

rier 15 against the energy of the spring 20, 65 thus bringing the sear-face 14 of the trigger-blade in position below the tailpiece e' of the left gun-lock without operating the trigger in an upward direction or moving it on the pivot 19. When the trigger and its carrier are shifted toward the left, the projection 24 of the trigger-blade engages with the shoulder 33 of the detent, said detent yielding in a backward direction to the pressure exerted on the beveled face of its lip 32 by the projection 70 24 of the trigger during the lateral shifting movement thereof. The detent and its lip 32 operate to hold the trigger and its carrier in the deflected position (indicated by dotted lines in Fig. 3) until it is desired to use the left-hand gun-lock, and in said adjusted position of the trigger the sear-face 14 of the trigger-blade lies below the tailpiece e' of said left-hand lock E until such time as it is desired to explode the charge in the left barrel. It 75 is only necessary to press upwardly on the trigger and turn it on the pivot 19 to operate the left-hand lock E, and during this upward movement the face 14 of the trigger engages with the sear-tail e' for the proper operation 80 of the lock E. When the trigger is raised, as just described, the projection 24 clears the shoulder 33 of the detent, thus allowing the spring 20 to become active in pressing the trigger and its carrier 15 back to the normal 85 position and toward the right-hand sear-tail e, the beveled rear face of the projection 24 riding on the beveled face of the lip 32, forming a part of the detent 25, so as to guide the trigger and insure its return to the normal 90 position below the right-hand sear e of the gun-lock D.

As hereinbefore indicated, an important feature of the invention is the construction and arrangement of the parts in a way to overcome a tendency to fire a second barrel by the involuntary pull—that is to say, when the trigger is operated to release one lock the tendency in the action of the gun is to throw the trigger to a position wherein it will operate the other lock immediately following the discharge of the first cartridge. To overcome this objection, which is a serious one in the class of single-trigger guns, I have arranged the trigger for operation in connection with the tailpieces e e' of the two gun-lock sears in such a way as to make the tailpieces operate as stops in limiting the lateral swinging movement of the trigger. Assuming that the trigger is operated to release the hammer of the right-hand lock, the pressure of the spring 20 tends to keep the trigger in position for its shoulder or blade 12 to lie below the tailpiece e. When the trigger is pulled laterally and rearwardly, the lateral movement thereof is arrested by the shoulder 110 12 coming into abutting engagement with the tailpiece e' of the left-hand lock-sear, said

tailpiece e' being disposed in a lower horizontal plane than the tailpiece e , whereby the shoulder 12 is caused to take a position below the tailpiece e' . It is evident that before the 5 left-hand lock can be operated by the trigger it is necessary for the operator to again pull the latter in a rearward direction, the detent serving as the means for holding the trigger in the laterally-deflected position toward the 10 left and in coöperative relation to the tailpiece of the left-hand lock. When the trigger is again pulled to operate the left-hand lock, the shoulder 14 is raised for the operation of the tailpiece e' and the projection 24 15 clears the shoulder of the detent, whereby the shoulder 12 of the trigger is raised above the tailpiece e' and into the plane of the tailpiece e . Now when the trigger is released and free from the restraint of the detent the 20 spring 20 acts to press the trigger toward the right-hand lock, and during this lateral return movement of the trigger the part 12 thereof strikes the tailpiece e , which temporarily arrests the movement of the trigger 25 toward the right, after which the spring 22 becomes effective, so as to depress the trigger and cause the shoulder 12 to take a position below the tailpiece e .

From this description it will be evident that 30 the arrangement of the tailpieces e e' in different horizontal planes makes them serve as stops in limiting the lateral swinging movement of the trigger, and by placing the shoulders 12 14 in different horizontal planes they 35 are caused to assume proper positions with relation to the tailpieces of the two sears for the operation of said sears when the trigger is operated in a predetermined manner by the sportsman, the entire group of devices operating in a way to overcome the tendency to 40 fire a second barrel by the involuntary pull.

Having thus described my invention, I claim as new and desire to secure by Letters Patent—

1. In a firearm, the combination with a plurality of sears having spaced tailpieces lying in different planes transversely of the firearm, of a laterally-shiftable carrier, a trigger mounted on said carrier for adjustment therewith, and provided with sear-faces located in 45 different horizontal and vertical planes, and adapted to have engagement individually with the tailpieces of said sears, means for holding said carrier and trigger in position for coöperation with one sear, and a detent adapted for 50 coöperation with said trigger when adjusted into coöperative relation with the other sear.

2. In a firearm, the combination with a plurality of sears, of a laterally-shiftable carrier, a trigger pivotally connected to said carrier 55 for movement therewith, means for holding said carrier in position for the trigger to operate with one sear, and a yieldable detent disposed for interlocking engagement with said trigger and lying in the path thereof dur-

ing the lateral shifting movement with the carrier, said detent being disposed to retain the trigger and carrier in position for coöperation with the other sear.

3. In a firearm, the combination with a plurality of sears having spaced tailpieces lying in different transverse planes, a laterally-shiftable carrier, a trigger having a blade which is provided with separate sear-faces and is arranged to play between the tailpieces of said sears, to be limited laterally thereby, a spring 75 for holding the trigger and carrier in one position, and a detent lying in the path of the trigger and arranged to have interlocking engagement therewith when adjusted to a laterally-shifted position wherein it is adapted for 80 coöperation with the other sear.

4. In a firearm, the combination with a plurality of sears having tailpieces, of a pivoted laterally-shiftable carrier, a trigger pivoted to said carrier for movement therewith and 85 having separate sear-faces arranged for coöperation individually with the tailpieces of the locks, a trigger-spring mounted on said carrier for adjustment therewith and having engagement at all times with the trigger, means 90 for holding the carrier and trigger in position for coöperation with one sear, and a detent disposed to retain the trigger in operative relation to the other sear.

5. In a firearm, the combination of a pair of 9 sears, a trigger-plate, a spring-actuated carrier mounted on said trigger-plate for laterally-shifting movement thereon, a stop-pin of small area for arresting the movement of the carrier in one direction under the action of its 10 spring, a trigger pivoted to said carrier for adjustment therewith, and a detent for retaining the trigger in coöperative relation to one of the sears.

6. In a firearm, the combination of a plurality of sears having tailpieces disposed in different horizontal planes, a single trigger capable of a lateral shifting movement and operable between said tailpieces of the sears, said trigger being provided with shoulders disposed at different elevations and adapted for individual coöperation with said tailpieces.

7. In a firearm, the combination of a plurality of sears having tailpieces disposed in different horizontal planes, a single trigger capable of a lateral shifting movement and operable between said tailpieces of the locks, said trigger being provided with shoulders disposed at different elevations and adapted for individual coöperation with said tailpieces, and a detent slidable with relation to the path of shifting movement of said trigger and arranged to hold the latter in position for operating the tailpiece of one of said sears.

8. In a firearm, the combination of a plurality of sears having tailpieces, a pivoted carrier, a trigger pivoted to said carrier and having sear-faces disposed in different planes and

adapted for coöperation individually with the tailpieces of the sears, a spring acting on the carrier, another spring mounted on the carrier and acting on the trigger, and a detent disposed in the path of the trigger and adapted to retain it in coöperative relation to one of said sears.

In testimony whereof I have signed my name to this specification in the presence of two subscribing witnesses.

HENRY EDWARD WINANS.
